JEWELRY

Herbert L. Miskend, New York, N. Y., assignor to
 Lande & Miskend, Inc., New York, N. Y., a
 Corporation of New York

Application January 23, 1933. Serial No. 652,992

10 Claims. (Cl. 63—16)

This invention relates to an improvement in articles of jewelry and more particularly to a jewelry clip which can also without modification be used as a finger ring.

5 A particular object of this invention is the provision of a novel form of jewelry clip to be used for the holding or fastening of undergarments, lingerie or overgarments. Said clip is ornamental and it may also be used when desired as a finger ring.

Further objects of the invention will be apparent from the specification and drawing in which Fig. 1 shows in perspective the application of the invention as a clasp for wearing apparel.

15 Fig. 2 is a perspective view showing the use of the invention as a finger ring.

Fig. 3 is a front elevation of the article.

Fig. 4 is a side elevation of the article in closed position, and

20 Fig. 5 is an end elevation.

Fig. 6 is a detail view of one form of jewel or ornament.

Fig. 7 is a detail plan view of one of the clip members.

25 Fig. 8 is a detail plan view of the other of the clip members.

Fig. 9 is a front elevation of a rectangular embodiment of my invention. Many modifications of the shape of the article may be made without departing from the spirit of my invention.

30 Fig. 10 is a view similar to Fig. 4 but showing the clip in an open position.

Essentially my improved combination clip and ring comprises three parts, the jewel or ornament

35 11, the rear half of the clip denominated 12, and the front clip member 13, as shown in Fig. 10.

The ornament 11 is provided with a bore or perforation 14, and said bore preferably has enlarged ends 15, as shown in Fig. 6.

40 It should be noted that this jewel 11 may be of any design or shape in harmony with the general appearance, color, and shape of the clip itself. For illustrative purposes in Figs. 1-9 inclusive, a clip member made of wire having a circular cross-section is shown, but the wire may be square in cross section.

45 As shown in Figs. 7 and 8, each clip-member has a body 16, one end of which has an eye 17. This eye 17 is connected to the adjacent end of body 16 by means of a shank 19. At its other end, the body 16 has a lug 20, provided at one end with a pin 21. Said lug 20 has a head 18.

50 When the clip members 12 and 13 are assembled with the jewel 11, said members 12 and 13 have the relative positions shown in Figs. 7 and 8,

the eye 17 of one member being adjacent the lug 20 of the other member. The pin 21 of each member is passed through the eye 17 of the other member, thus permitting the members 12 and 13 to be turned relative to each other.

60

Each member 16 is provided with a spring 24 above the lug 20, and each said spring bears against the adjacent top end 25 of the other member 16. Said springs 24 force the clip members into the position shown in Fig. 4. The clip members are provided with cooperating prongs 22 and recesses 23.

65

The members 12 and 13 may be generally described as "loop-shaped" members, although they are not closed loops.

70

Each of said members 12 and 13 is made of bendable or springy wire, so that their ends may be separated so as to permit the pins 21 to enter the bore 14 of the ornament 11.

75

It will be apparent that further changes and modifications may be made in this form of combination clasp and ring without departing from the spirit of my invention.

75

Having fully described my invention, what I claim is:

80

1. An article of jewelry comprising two complementary loop shaped members having their sides parallel to each other, one of said loop shaped members being provided with prongs, the other of said members being provided with corresponding recesses, and an ornamental mounting joining said two loop shaped members and means to keep said loop members in contact with each other.

85

2. A combination clasp and ring comprising two equal and complementary loop shaped members having their sides adjacent to each other, an ornament mounted in the opening of said loops, pintles joining said ornament and the free ends of said loop shaped members, and springs adjacent said ornament to keep said loop shaped members in contact with each other.

90

3. A combination clasp and ring comprising two equal and complementary loop shaped members having their sides adjacent to each other, an ornament mounted in the opening of said loops, pintles joining said ornament and the free ends of said loop shaped members, springs adjacent said ornament to keep said loop shaped members in contact with each other, prongs in one of said loop shaped members and corresponding recesses in the opposite member to receive said prongs.

95

4. In combination, an ornament, clasp members having pins which enter said ornament, said clasp members being turnable relative to each

100

105

110

other, said ornament extending above and below said pins, said clasp members having cooperating means adapted to engage a garment.

5. In combination, an ornament, clasp members having pins which enter said ornament, said clasp members being turnable relative to each other, said clasp members being loop-shaped and corresponding to sections of a ring, so that the device can be worn as a ring when the clasp members are close to each other, said clasp members having cooperating means adapted to engage a garment.

10 6. In combination, an ornament, clasp members having pins which enter said ornament, said clasp members being turnable relative to each other, and spring means external to said ornament and adapted to urge said clasp members towards each other.

15 7. In combination, an ornament, clasp members each of which has separated ends, said clasp members being of like construction, each said clasp member having an eye at one end thereof and a pin connected to the other end thereof, said ornament having a bore in which said pins can be located when the device is assembled, each pin passing through the eye of the other clasp member when the device is so assembled.

20 8. In combination, an ornament, clasp members each of which has separated ends, said clasp members being of like construction, each said clasp member having an eye at one end thereof and a pin connected to the other end

thereof, said ornament having a bore in which said pins can be located when the device is assembled, each pin passing through the eye of the other clasp member when the device is so assembled, the length of each pin being less than the length of the bore.

25 9. In combination, an ornament, clasp members each of which has separated ends, said clasp members being of like construction, each said clasp member having an eye at one end thereof and a pin connected to the other end thereof, said ornament having a bore in which said pins can be located when the device is assembled, each pin passing through the eye of the other clasp member when the device is so assembled, and spring means located external to said ornament and adapted to turn said clasp members towards each other.

30 10. In combination, an ornament, clasp members each of which has separated ends, said clasp members being of like construction, each said clasp member having an eye at one end thereof and a pin connected to the other end thereof, said ornament having a bore in which said pins can be located when the device is assembled, each pin passing through the eye of the other clasp member when the device is so assembled, each said clasp member having a closing spring connected thereto adjacent the base of its pin and bearing against the adjacent end of the other clasp member.
